Primary Examiner — Jeffrey D Asch*(74) Attorney, Agent, or Firm* — Finnegan, Henderson, Farabow, Garrett & Dunner, LLP(57) **CLAIM**

The ornamental design for a phone, as shown and described.

DESCRIPTION

FIG. 1 is a front left bottom perspective view of a phone showing my new design;

FIG. 2 is a rear right bottom perspective view thereof;

FIG. 3 is a front elevation view thereof;

FIG. 4 is a rear elevation view thereof;

FIG. 5 is a right side elevation view thereof;

FIG. 6 is a left side elevation view thereof;

FIG. 7 is a bottom plan view thereof;

FIG. 8. is a top plan view thereof; and,

FIG. 9 is an enlarged rear elevation view of a section indicated in FIG. 4.

The broken lines of uneven length shown in the drawing are used to isolate the portion of the rear shown in an enlargement in FIG. 9. The broken of even length shown in the drawings illustrate portions of the phone that form no part of the claimed design.
